Des. 194,808
Patented Mar. 12, 1963

194,808

BOTTLE CRATE

Frank W. Stevens, Rutherford, Albert Spaak, Little Falls,
William J. Lawrence, Jr., Clifton, and Bartholomew M.
Ficarra, Great Notch, N.J., and George H. Filipowski,
New York, N.Y., assignors to W. R. Grace & Co.,
New York, N.Y., a corporation of Connecticut

Filed Aug. 13, 1962, Ser. No. 71,240

Term of patent 14 years

(Cl. D58—5.1)

FIG. 1.

Des. 194,808

PAGE 2

FIG. 2

Des. 194,808

PAGE 3

FIG. 3

FIG. 4

FIGURE 1 is a top perspective view of a bottle crate, showing our new design, in partially open condition;

FIGURE 2 is a top plan view thereof in fully open condition;

FIGURE 3 is a bottom plan view thereof; and

FIGURE 4 is an enlarged, cross-sectional view thereof in partially open condition.

We claim:

The ornamental design for a bottle crate, as shown.
